(57) **CLAIM**

The ornamental design for a medical connector for a blood glucose meter as shown and described.

DESCRIPTION

FIG. 1 is a top perspective view of a medical connector for a blood glucose meter showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view of the medical connector for a blood glucose meter of FIG. 1; and,

FIG. 9 is a perspective view of the medical connector for blood glucose meter shown in its environment.

The broken lines shown in the drawings are included for the purpose of illustrating environmental structure and unclaimed portions of the medical connector for a blood glucose meter and form no part of the claimed design.
